(57) **CLAIM**

The ornamental design for a display screen or portion thereof with graphical user interface, as shown and described.

DESCRIPTION

The FIG. 1 is a front view of a display screen or portion thereof with graphical user interface, showing my new design; and,

The FIG. 2 is a front view thereof, in which mobile terminal in broken lines is provided to illustrate an example environment.

The broken lines represent a boundary of the claim and forms no part of the claimed design.

The size and scale of the design within the environment of use in FIG. 2 form no part of the display screen or portion thereof with graphical user interface.
